UNITED STATES PATENT OFFICE.

GEORGE A. TAYLOR, OF BOSTON, MASSACHUSETTS.

MATCH.

Application filed August 4, 1927. Serial No. 210,675.

This invention relates to matches and their method of manufacture, and has for its chief object the improvement of the stick or splint on one end of which the ignitable head is placed.

More particularly it has for its object the provision of a splint which will not break when subjected to the stresses incident to striking, or which may be met with in handling and transporting, and which contains sufficient inflammable material to maintain the flame for the desired length of time.

It is also an object of this invention to provide a match having the desirable characteristics above enumerated which shall be cheap to manufacture and which lends itself readily to the manufacture of matches in card form as well as in individual units.

According to this invention, therefore, the match splint is composed of a fibrous pulp such as a light cheap paper pulp surrounding a metal wire core which gives the splint sufficient strength to resist breakage when the match is struck. When the matches are made in card form the wires for the several splints terminate at about the termination of the line of division between adjacent matches so that they may be detached readily from their supporting base as required.

The matches so constructed may be made by bringing together in face to face relation a pair of wet cellulosic pulp webs as received from the forming mechanism of a paper machine, the wires being deposited therebetween properly spaced so that when the webs are compacted together the material may be severed more or less completely between the wires to form individual matches joined at one end in card form.

After the pulp splint with the wire embedded therein is dry it may be treated in any suitable way to form the igniting head on one end and preferably is saturated adjacent to the head with paraffin or like agent so that the flame may endure for the desired period of time after the head has been ignited.

For a more complete understanding of this invention reference may be had to the accompanying drawings in which

Figure 1 is a fragmentary perspective illustrating the splint material in successive stages of manufacture.

Figure 2 illustrates diagrammatically the successive steps in such manufacture.

Figure 3 shows in perspective an individual completed match.

Figure 4 shows in perspective a card of matches.

Figure 5 is a section on line 5—5 of Figure 4.

Figure 6 is a section much enlarged of a form of wire which may be used.

Referring first to Figure 2, at 1 is indicated a sheet of wet pulp supported on a blanket 2 as it comes from the forming mechanism of the paper machine, the pulp and blanket passing about a supporting roller 3, the pulp being deposited on the outer face of a drum 4 while the blanket returns about the roller 3. At 5 is shown a hopper in which may be placed a supply of lengths of reinforcing wire which pass down through a chute 6 in proximity to the periphery of the drum 4. This drum 4 has transversely extending grooves 7 at suitable intervals extending parallel to its axis in each of which a wire 8 is adapted to be deposited from the chute 6 and fed around as the drum 4 is rotated to bring the wires into contact with and partially embed them in the face of the wet web 1 as it is laid on the drum. The web with the wires thus partially embedded therein is removed from the drum 4 to a suitable support as at 9, and a second wet web of pulp shown at 10, supported on a blanket 11, is fed around a roller 12, and is deposited in superposed relation onto the web 1 and the wires 8 partially embedded therein. The two webs are then compacted together and partially or completely severed between the wires as by means of the compacting roller 15 having the cutting elements 16 arranged on the periphery thereof.

In Figure 1 the relation of the webs and the wires in their successive operations is shown where it is desired to make the matches in card form. It will be noted that where this is done the wires 8 are of less length than the width of the web and are positioned along one edge portion thereof so that when the combined materials are cut as at 20 by the cutter 16, the cuts extend from the edge along which the wires are placed toward the opposite edge a distance substantially equal to the length of the wires. By this means each splint formed between the cuts 20, as shown at 21, contains a wire embedded therein, which extends from adjacent its free end 110

to about the end of the severance lines between successive splints. By this construction the splints may be broken off at their bases from the uncut margin quite readily 5 when desired.

Where it is desired to make the matches as individual units, the wires may be made substantially the length of the web width and the cuts may be extended entirely across 10 the web to form individual units such as are shown in Figure 3, which when the pulp has dried may be provided with the igniting heads as shown at 25. When the matches are made in card form the splints 21 are 15 bent alternately in opposite directions and are provided with the heads as shown at 26 in Figure 4. Preferably also the material adjacent to the heads is saturated with paraffin in order that combustion may be 20 better supported and the flame caused by the ignition of the heads prolonged the desired length of time and without burning an excessive length of splint material.

If desired the wires may be formed in 25 other than circular cross section, particularly if it is desired to effect a more tenacious bond between the wires and the pulp material. They may be formed if desired with projections engaging into the pulp webs, as for 30 example, with longitudinally extending ribs as 30 as shown in Figure 6. In order that proper stiffness may be imparted by the wires to the splints, it is preferable to form the wires of steel and from .02 to .025 inches 35 in diameter, this corresponding to wires of gage numbers from about 22 to 25.

The pulp stock should be soft, cheap material which is well adapted to receive the paraffin, but which of itself would be of insufficient strength to stand the strain incident to striking. 40

Having thus described certain embodiments of this invention, it should be evident to those skilled in the art that various

changes and modifications might be made 45 therein without departing from its spirit or scope as defined by the appended claims.

I claim:

1. A match having a splint portion provided with a metallic reinforce. 50

2. A match having a splint portion formed of a wire overlaid with combustible material.

3. A match having a splint portion formed of wire overlaid with cellulosic pulp. 55

4. A match having a splint portion formed of a wire positioned between interfelted layers of cellulosic pulp.

5. A match having a splint comprising a wire having projecting portions, said wire 60 being surrounded by interfelted fibrous material.

6. A match having a splint comprising a longitudinal ribbed wire, said wire being surrounded by cellulosic pulp. 65

7. A match card comprising a sheet of cellulosic material partly divided into individual splint portions, each splint portion having a wire incorporated therein. 70

8. A match card comprising a sheet of interfelted cellulosic material cut partly across from one edge to define a series of splints adapted to be broken from the sheet as desired, each of said splints being reinforced longitudinally throughout substantially the length of the cuts with a wire. 75

9. A match card comprising a sheet of interfelted cellulosic material cut partly across from one edge to define a series of splints adapted to be broken from the sheet as desired, each of said splints being reinforced longitudinally throughout substantially the length of the cuts with a wire embedded therein. 80

In testimony whereof I have affixed my 85 signature.

GEORGE A. TAYLOR.
